UNITED STATES PATENT OFFICE.

JACOB WILDENBERG, OF NEW YORK, N. Y., ASSIGNOR TO WILDENBERG BROS., OF NEW YORK, N. Y., A FIRM COMPOSED OF JOSEPH WILDENBERG, JACOB WILDENBERG, AND CHARLES WILDENBERG.

DESIGN FOR A BEZEL.

55,926.

Specification for Design.

Patented July 20, 1920.

Application filed April 13, 1920. Serial No. 373,562. Term of patent 7 years.

To all whom it may concern:

Be it known that I, JACOB WILDENBERG, a citizen of the United States, residing at the city of New York, borough of Bronx, and State of New York, have invented a new, original, and ornamental Design for a Bezel, of which the following is a specification, reference being had to the accompanying drawing, forming part thereof.

Figure 1 is a plan view of the bezel, showing my new design, and

Fig. 2 is a cross-section on the line 2—2 of Fig. 1.

I claim:—

The ornamental design for a bezel, as shown.

JACOB WILDENBERG.
